UNITED STATES PATENT OFFICE.

ALFRED B. ESSELTINE, OF CHICAGO, ILLINOIS, ASSIGNOR TO GOODMAN MANUFACTURING COMPANY, OF CHICAGO, ILLINOIS, A CORPORATION OF ILLINOIS.

LOADING BOOM.

Application filed March 4, 1926. Serial No. 92,153.

This invention relates to improvements in apparatus for handling loose material and has among other objects to provide a new and improved loading boom for a device of this 5 class, such as described in the application of Charles E. Davis bearing Serial Number 352,413, filed January 19, 1920.

My invention may be best understood by reference to the accompanying drawings 10 wherein:

Figure 1 is a plan view of the device embodying my invention;

Figure 2 is an enlarged fragmentary view of Figure 1;

15 Figure 3 is a side elevation of the view shown in Figure 2;

Figure 4 is a section taken on line 4—4 of Figure 1 showing the pivotal connection of the spring stop to the loading boom;

20 Figure 5 is a section taken on line 5—5 of Figure 1 showing the adjusting mechanism for the boom; and

Figure 6 is a fragmentary view of the 25 spring stop.

In these drawings, the embodiment of my invention illustrated in Figures 1, 2 and 3, includes an inclined guide 1 extending longitudinally over a power device having means to reciprocably move and control a scraper 2. This device is preferably used to gather 30 coal in mines and is fully described in the application of Charles E. Davis, Serial Number 352,413, filed January 19, 1920, previously referred to herein. It is therefore 35 unnecessary to give details of the power device herein, excepting such as are essential to the present invention.

The power device above referred to is portable and can be moved with its scraper and 40 guiding means to different sections of the mine. A loading boom 3 extends to the rear of the inclined guide 1 and is adapted to slide longitudinally thereon, as will now be described in detail.

45 The loading boom 3 (Figures 1, 2 and 3) comprises two side members 5, 5 connected at their rear end by a cross member 6. These side members fit and are capable of being moved longitudinally in guides 4, 4 (Figure 50) on each side of the incline 1. A sheave

7 is mounted to the rear of the cross member 6, preferably at the longitudinal center thereof. The boom is particularly designed for cooperation with a head rope 8, which is shown herein as passing from the top of a 55 head rope drum 9 backwards to the sheave 7, over said sheave and forward to the scraper 2.

Means are preferably provided for positively moving the loading boom 3 longitudinally in the guides 4, 4. In the construction 60 shown, I provide a rack and pinion for this purpose. The side members 5, 5 of the boom 3 are preferably made up of channel irons having flanges extending outwardly. (Figures 1 and 5). A rack 16 is mounted to the upper 65 surface of the lower flange of each longitudinal channel member 5. A pinion 17 meshes with the rack 16 and is keyed to a shaft 18 which is carried in a bracket 19 adjacent the rear of the incline 1. A crank 20 is removably attached to the shaft 18. Rotation of the 70 cranks 20, 20 on each side of the incline 1 rotate the pinions 17, 17 which move the racks 16, 16 and thus move the loading boom 3 longitudinally in its guides.

A movable locking piece 24 is pivoted at 75 25 and engages a holding piece 26 which fits into a recess 27 in the locking piece 24. When the parts are in their operative position the locking piece is in the position shown in Figure 3. When it is desired to move the boom in out of the way it is first moved outwardly to release the shoulder 27 from the holding piece 26. The locking piece 24 may then be moved about its pivot to a position where it will not strike the holding piece and then the boom may be moved to its inoperative position by turning the cranks 20.

A stop 10 is placed on each side of the rear cross member 6 to stop the scraper 2. Said 80 stops comprise a rod 28 which projects forwardly of the cross member 6 and is capable of sliding longitudinally in guide holes 29 and 30. A forward end 34 of the rod 28 is bent at right angles and extends in toward the center of the boom to catch and stop the scraper when it reaches the end of its forward movement. A collar 35 is fastened to the forward end of the rod 28. A spring 36 is interposed between this collar and the guide 95 100

30. The guide 30 is pivotally mounted to a bracket 37 by a pivot pin 15. To fold the stops 10 in out of the way, the rod 28 is pulled forward until it disengages the guide 29. The 5 stop can then be pivoted in toward the center of the loading boom.

The arrangement of these spring stops so 10 cushions the load as to prevent its being scattered when the scraper is stopped, and lessens the liability of damage to the scraper or loading boom and prevents breakage of the head rope.

The operation of the device above described is as follows:

15. The head rope 8 draws the loaded scraper up the incline until it hits and is stopped by spring bumpers 10, 10 on each side of the rear cross member 6. The scraper 2 is preferably of the V type having an open bottom so as to 20 allow its load to drop through an opening 14 into a suitable receiving device (not shown) when drawn over that opening.

It will here be seen that the opening 14 has no obstruction to hinder the coal from being 25 freely discharged from the scraper 2. Other constructions of loading booms performing the same duty, and more particularly the construction used in Davis application, Serial Number 352,413, comprise an extension arm 30 which extends longitudinally backwards from the center of the inclined guide chute and carries a sheave at its rearward end. This central extension arm hinders the discharge of the load from the scraper since the 35 loaded scraper must straddle this arm. This causes the load to be split as it drops to the receiving device below. It also makes it difficult to load lump coal as the lumps are either broken by their impact with the arm when 40 drawn up on the arm or when caught between the scoop and arm when the scoop is initially drawn back to its loading position. The construction herein set forth eliminates these disadvantages and makes it possible to efficiently 45 load a receiving device such as a mine car without breaking or splitting the lump coal.

Since my invention is preferably used on a portable loading machine which is often moved about in a mine where the head room 50 is restricted, it is necessary that it take up as little space as possible while the loading machine is being transported from place to place. This is accomplished by sliding the boom 3 forward in the guides 4. The spring bumper 55 10, 10 pivots on the pins 15 and folds in out of the way to allow a maximum forward movement of the boom 3 in the guides 4.

Although I have shown and described one 60 form in which my invention may be embodied, it will be understood that the construction and arrangement of the different parts may vary widely without departing from the spirit and scope thereof. Furthermore, I do not wish to be understood as limit-

ing myself to the specific construction illustrated herein, excepting as it may be limited in the appended claims.

I claim as my invention:

1. The combination with a scraper loading apparatus of an inclined guide, a loading boom sliding longitudinally in guides in the outermost extremities of said incline, and resilient stops for said scraper comprising elongated compression members pivotally mounted to extend longitudinally of said guide when in operative position but adapted to be swung into transverse position when the boom is telescoped.

2. The combination with a scraper loading apparatus of an inclined guide, a loading boom sliding longitudinally in guides in the outermost extremities of said incline, and resilient stops for said scraper comprising spring members on pivotally mounted rods adapted to extend longitudinally of said guide when in operative position but adapted to be swung into transverse position when the boom is telescoped.

3. The combination with a scraper loading apparatus of an inclined guide, a loading boom sliding longitudinally in guides in the outermost extremities of said incline, and resilient stops for said scraper comprising compression spring members mounted on rods slideable in pivotally mounted brackets, one 90 end of said rods being adapted to engage the forward end of a scraper and the rearward portion of the scraper engaging end of said rod engaging said compression spring, the other end of said spring engaging said 95 bracket.

4. The combination with a scraper loading apparatus of an inclined guide, a loading boom sliding longitudinally in guides in the outermost extremities of said incline, resilient 105 stops for said scraper comprising compression spring members mounted on rods slideable in pivotally mounted brackets, one end of said rods being adapted to engage the forward end of a scraper and the rearward portion of the scraper engaging end of said rod engaging said compression spring, the other end of said 110 spring engaging said bracket, and means for holding said stops in a position longitudinally of said boom when in operative position or allow said stops to swing in a transverse position when said boom is telescoped.

5. The combination with a scraper loading apparatus, of an inclined guide, a loading boom extending to the rear of said incline and having telescopic connection with the sides of said incline comprising a rectangular frame having a sheave in the central rearward portion thereof and resilient stops projecting forwardly from each rearward inner corner 115 thereof.

6. The combination with a scraper loading apparatus, of an inclined guide, a loading

boom extending to the rear of said incline and having telescopic connection with the sides of said incline comprising a rectangular frame having a sheave in the central rearward portion thereof and resilient stops at each rearward inner corner thereof pivotally mounted to extend longitudinally of said guide when in

operative position, but adapted to be swung inwardly as said boom is telescoped into said incline.

Signed at Chicago, in the county of Cook and State of Illinois, this 1st day of March, 10
A. D. 1926.

ALFRED B. ESSELTINE.
